(57) CLAIM

The ornamental design for a door for vehicle, as shown and described.

DESCRIPTION

FIG. 1 is a perspective view of a door for vehicle, showing our new design;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a rear view thereof.

The broken lines and the de-emphasized areas bound by the broken lines show portions of the door for vehicle and do not form part of the claimed design.

1 Claim, 5 Drawing Sheets
